US0D1059382S

(12) **United States Design Patent** (10) **Patent No.:** **US D1,059,382 S**
(45) **Date of Patent:** **** Jan. 28, 2025**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Jared Andrew Crawford**, Apex, NC (US); **Christian Xavier Dalonzo**, San Francisco, CA (US); **Robert Garcia, III**, San Francisco, CA (US)

(73) Assignee: **Apple Inc.**, Cupertino, CA (US)

(**) Term: **15 Years**

(21) Appl. No.: **29/853,766**

(22) Filed: **Sep. 19, 2022**

Related U.S. Application Data

(63) Continuation of application No. 29/829,694, filed on Mar. 7, 2022, now Pat. No. Des. 964,396, which is a continuation of application No. 29/738,902, filed on Jun. 20, 2020, now Pat. No. Des. 947,866.

CLAIM

The ornamental design for a display screen or portion thereof with graphical user interface as shown and described.

DESCRIPTION

The FIGURE is a front view of a display screen or portion thereof with graphical user interface showing the claimed design.

The outer broken lines in the FIGURE show a display screen or portion thereof, and form no part of the claimed design. The other broken lines in the FIGURE show portions of the graphical user interface that form no part of the claimed design.
